ELECTRICAL CONTROL APPARATUS FOR
HEATING PLANTSPetter Hartmann-Riis, Ostre Aker, near Oslo,
NorwayApplication February 15, 1937, Serial No. 125,870
In Norway February 14, 1936

3 Claims. (Cl. 236—1)

(Granted under the provisions of sec. 14, act of
March 2, 1927; O. G. 5)

The present invention relates to electrical control systems for regulating the temperature or pressure in hot water or steam heating plants.

It is known in oil fired heating plants to effect such control by controlling the flame with a mercury switch, which at a fixed temperature in the boiler or in the rooms, which are to be heated or at a fixed pressure in the boiler disconnects the current to the motor which drives the oil pump and the air fan for the admission of oil and air respectively to the burner, whereby the flame will be entirely extinguished. When the temperature has declined to a certain point the current circuit again will be closed, the motor starts and a full flame will again be established.

This complete and frequent extinctions and ignitions to complete flame have considerable drawbacks, as each ignition will cause a considerable amount of atomised oil-air-mixture to be blown into the fire box before ignition takes place, and which therefore will not be utilised and the temperature of the exit gases will be high, as the burner, when burning, always has a complete flame. Furthermore the working of the plant will be irregular, owing to the irregular heat supply.

It has previously been suggested to obtain a completely regular working of an oil fired plant by varying the size of the flame in accordance with the momentary heat requirement.

Thus it is known to let the oil be drawn into the burner by the inflowing air, the quantity of which oil supply is controlled by a damper, the opening of which is controlled by a temperature influenced organ. However, this aspiration of the oil to the burner by the air has several drawbacks as compared with pumping. The same considerations apply to motor driven, stokers in coal fired plants.

The object of the present invention is to provide apparatus for electrically controlling the temperature or pressure in hot water or steam generating plants, in which both the oil pump and the air fan, which pass oil or air respectively to the burner, are driven by a common motor. According to the invention the velocity of motor and thereby the size of the flame is controlled by connecting in series two or more temperature responsive switches, one of which has an operative range which covers the range of all the others or the apparatus may consist of only one switch with stagewise control.

In case of several switches, one has an operative range, of such scope as to embrace the operative range of the other switch or switches. The

switch or switches with the intermediate operative ranges are connected in parallel with resistances, in which the current flows when the switch is disconnected, while the switch with the widest operative range either is completely disconnected or connected with or without resistance connected in series.

In case of only one switch for the stagewise control, the motor current in one of the stages passes through the switch without resistance, while in the other stages passing through one or more resistances connected in series with the switch.

In the accompanying drawing several embodiments of the invention are shown for regulating the temperature or pressure of steam or hot water boilers.

Fig. 1 shows diagrammatically the apparatus with two switches for regulation in two steps.

Fig. 2 shows the apparatus with one switch for regulation in two steps.

Fig. 3 illustrates apparatus with two switches for regulation in three steps and

Fig. 4 shows a device similar to Fig. 1, in which a transformator is used for the voltage regulation.

In Fig. 1, 1 is the motor which drives the pump and the fan for passing oil and air to the burner, 2 and 3 are switches, which here are shown as the mercury type operated by thermostats and 4 is an adjustable resistance connected in parallel with the switch 3. The circuit is clearly shown in the figure. The thermostat operating the switch 2 is adjusted to have an operative range between 40° and 50° centigrade, or interruption will take place at 50° and connection again established at 40°, while the thermostat operating the switch 3 has an operative range between 41° and 43° centigrade. When the temperature in the boiler rises, the switch 3 will open the circuit 16 at 43°, but the current will not be interrupted, as it flows through the resistance 4 whereby the current, the number of revolutions of the motor and the size of the flame decrease.

The size of the reduced flame may be controlled by adjusting the resistance 4. However, the temperature of the water in the boiler continues to rise owing to the radiance from the masonry below the boiler, even if the size of the flame has decreased. If the temperature increases for example to 47° and then decreases the switch 3 will close the circuit 16 at 41° which results in a complete flame and increasing temperature. If, on the other hand, the temperature increases

to 50°, then the switch 2 will open the circuit 17 and the flame will be extinguished. If the temperature decreases to 40°, the switch 3 will have closed the circuit 16 at 41°, and the flame will ignite, and then burn with complete flame, since the switch 2 closes at 40°. Experience has shown, that extinction of the flame practically does not occur when the operative ranges of the two switches 2 and 3 and the size of resistance 4 are adequately adjusted.

Fig. 2 shows apparatus, with which the same effect is obtained as with the apparatus shown in Fig. 1 with only one temperature responsive switch. As will be seen, the thermostat operated switch here has three lines 5, 6, 7. With the position shown in Figure 2 the current passes through lines 5 and 6 without passing through any resistance, but when the mercury level has the position shown in dotted lines or the 45° centigrade position the current passes through the resistance 4 and the current declines. At 50° the thermostat operated switch becomes wholly inactive and will move to the position, shown in Fig. 2 when the temperature has declined to 40°.

Fig. 3 shows a combination of the arrangement shown in Figs. 1 and 2 with two temperature responsive switches, in which the flame is regulated in three steps. The switch 30 is here the same as 3 in Fig. 1, while the thermostat of switch 20 is the same as in Fig. 2. When the switch 30 responds, at 43°, the circuit will be closed over the resistance 4, and thereby the size of the flame will decline as described in connection with Fig. 1. By continued rise of the temperature, for example at 45° the resistance 50 will become part of the circuit, and at 50° the current will be cut off by the switch 20. During cooling the switch 30 will close at 41°, but the circuit will be closed without including resistances, since the switch 20 also returns to its initial position, at 40°.

It is clearly understood that the requisite number of regulation steps may be acquired by an adequate choice of thermostats or switches and their number.

Fig. 4 shows as an example how the voltage regulation may be effected, by connecting the motor circuit across different voltage types of the secondary winding of a transformer 46. The switch 31 in responding will be completely turned over, thereby connecting the lower voltage of the secondary winding of the transformer across the motor, whereby the number of revolutions of the motor will be reduced the thermostat associated with the switch 21 being similar to that described in connection with switch 2 in Fig. 1.

The temperatures referred to in the specification relate to the centigrade scale and the switches operating at the temperatures indicated are to be regarded as exemplary. The sequence from which the thermostatically operated switches function is of fundamental importance in carrying out the objects of the invention and changes in adjustment of the switches and the consequent temperatures at which the switches operate may be varied without departing from the spirit and scope of the invention as long as the hereinabove described steps or sequence is maintained.

I claim:

1. Apparatus for automatically controlling the heat output of an oil fired heating plant having the oil supplied thereto by a pump and a fan driven by a single motor comprising an electrical supply circuit having one side thereof connected to one terminal of the motor, a circuit extending from the other motor terminal adapted to be connected to the other side of the supply line, voltage limiting means associated with said second mentioned circuit, a thermo-responsive switch adapted to connect said second mentioned circuit to said supply circuit when a predetermined low temperature is reached and open said circuit when a predetermined maximum temperature is obtained from the heating plant, a second thermo-responsive switch associated with the motor circuit having an operable range intermediate of the operable range of the first mentioned switch, and said second mentioned switch being operable to connect said voltage limiting means in the motor circuit when a predetermined intermediate temperature is obtained from the heating plant.

2. Apparatus for automatically controlling the heat output of an oil fired heating plant having the oil supplied thereto by a pump and a fan driven by a single motor comprising, an electrical supply circuit having one side thereof connected to one terminal of the motor, a circuit extending from the other motor terminal adapted to be connected to the other side of the supply line, voltage limiting means associated with said second mentioned circuit, two thermostatically operated switches associated with said second mentioned circuit, one of said switches being adapted to open and close at temperatures which are respectively above and below temperatures which cause the second switch to open and close, the switch having the greater operative range being adapted to close the motor circuit across the supply line and open the same, and said switch having the intermediate range being operable to include said voltage limiting means in the motor circuit when the heat output of the plant has reached an intermediate predetermined temperature.

3. In apparatus for automatically controlling the heat output of an oil firing heating plant having the oil supplied thereto by a pump and a fan driven by a motor comprising, an electrical supply circuit, voltage limiting means, a switch operably responsive to a predetermined low temperature for connecting said motor across the supply circuit, a second switch operably responsive to a temperature higher than said predetermined low for impressing a lower voltage across said motor, said first mentioned switch being operable to disconnect said motor from the supply circuit at a predetermined maximum temperature, and said second mentioned switch being operable at a temperature slightly higher than said predetermined low temperature for eliminating the voltage limiting means whereby the motor will start on full line voltage when said first mentioned switch reaches said predetermined low temperature.

PETTER HARTMANN-RIIS.
